Primary Examiner — David G Muller*Assistant Examiner* — Nathan M Johnston(74) *Attorney, Agent, or Firm* — Keisling & Pieper PLC; David B. Pieper**CLAIM**

The ornamental design for a string groove masonry clamp, as shown and described.

DESCRIPTION

FIG. 1 is a top perspective view of a string groove masonry clamp showing my new design;

FIG. 2 is a top plan view thereof;

FIG. 3 is a left side elevation view thereof;

FIG. 4 is a front elevation view thereof; and,

FIG. 5 is a right side elevation view thereof;

FIG. 6 is a rear elevation view thereof;

FIG. 7 is a bottom plan view thereof;

FIG. 8 is a bottom perspective view thereof; and,

FIG. 9 is an environmental view thereof.

The broken lines showing the masonry block and string are for the purpose of illustrating environmental structure and form no part of the claimed design.

1 Claim, 9 Drawing Sheets(56)
